FLOOR WAXER AND POLISHING MACHINE

Paul H. Chappell, Leaksville, N. C.

Application October 20, 1948, Serial No. 55,500

4 Claims. (Cl. 91—39)

1

My invention particularly relates to household appliances such as floor waxes, polishers, sanders and the like, which comprise a flat shoe adapted to be slid upon a flat surface and which shoe is covered by a suitable material such as wool, cheesecloth, sandpaper or similar strips of material, and my invention resides in providing a household appliance of this character in which the coverings for the shoe may be readily removed and securely fastened in position thereon.

It is therefore the principal object of this invention to provide a floor waxes in which the base thereof is formed primarily in two sections, one section forming a shoe to which the floor waxing or polishing fabric is secured and an upper base portion or casing which is removable from the shoe but is adapted to be securely fastened against the upper periphery thereof so as to engage and compress the ends of the fabric or other material therebetween and thereby securely fasten the fabric or the like to the face of the shoe. Another object resides in providing a floor waxes of the foregoing character in which the means for clamping the shoe portion and the upper portion of the base structure together serves the additional function of providing a bearing for a shaft by means of which the plunger in the wax reservoir formed in the shoe portion is actuated to force the wax outwardly through openings provided therefor in the shoe.

With the foregoing objects in view my invention includes the novel elements and the combinations and arrangements thereof described below and illustrated in the accompanying drawings, in which:

Fig. 1 is a perspective view, partially broken away, of a preferred form of my invention; Fig. 2 is a sectional view of the floor polisher and waxer of Fig. 1 taken longitudinally thereof or in about the plane 2—2 of Fig. 1; and Fig. 3 is a fragmentary sectional view taken transversely of the machine and through the wax reservoir.

It will be understood that the present invention is designed to rest upon a floor or other flat surface and to be moved about in such manner as to distribute wax thereover while the operator walks about the floor. Therefore, it is desirable that the casing of the machine be of substantial weight, and it is also desirable that the pressure exerted upon the wax in the reservoir may be readily regulated and positively secured. Hence, the machine of the present invention comprises a base which is formed of two parts, one part thereof comprising a shoe 1 which is preferably of substantial thickness and mass and has a

2

cylinder 2 upstanding therefrom and preferably formed integral therewith. The other portion of the base comprises a casing 3 which is preferably of substantial weight and at the bottom thereof conforms generally in configuration to that of the shoe 1, the lower and peripheral edge of the casing 3 being designed to fit within a rib 4 which extends peripherally of the shoe 1.

The cylinder 2 is internally threaded as indicated at 5 and forms a reservoir for wax or other fluid substances, and a piston 6 is provided with a threaded periphery adapted to engage the threaded interior of the reservoir. One or a plurality of openings 7 are provided in the shoe 1 at the base of the reservoir through which the wax or other substance may flow to the material or fabric surrounding the shoe. For wax distribution purposes, a strip of felt 8 is preferably secured against the shoe, and for polishing purposes a strip of wool 9, cheesecloth or other suitable flocculent material is secured to overlie the felt. Sandpaper may be substituted for the outer strip depending upon the needs of the user.

Preferably, the inner felt strip is secured to the face of the shoe by any suitable adhesive, while the outer strip is removably secured thereto by the casing 3, as above described.

In order to clamp the material 9 securely between the shoe 1 and casing 3, I preferably provide an opening in the upper part of the casing which is sufficiently larger in diameter than the exterior of the reservoir as to permit the flange of a cover to extend therebetween, as clearly shown in Fig. 2. The outer and upper end of the reservoir 2 is screw-threaded as indicated at 10 and the interiorly threaded flange of a screw cap 11 is adapted to engage the exterior threads of the reservoir so that the outer shoulder 12 of the screw cap will engage the casing 3 and thereby effect a compression of the material 9 between the casing and the shoe. The cap has wings 22 formed thereon to facilitate manual manipulation thereof.

The screw cap 11 is provided with a central opening 13 therein through which the upper cylindrical end of a shaft or piston rod is adapted to extend. The lower polygonal section 14 of the shaft passes through an opening in the piston 6 of like configuration so as to impart rotary movement thereto. Preferably, the shaft is provided with a collar 15 adapted to engage the bottom of the screw cap and, at the lowermost end of the shaft, I preferably provide a pin 16 to prevent the shaft from being withdrawn from the piston. An operating handle 17 is fastened to the cylin-

cylindrical portion 13 of the shaft by means of a pin 18 passing through the shank of the handle and through a transverse passage in the cylindrical end 13 of the shaft.

Spaced, parallelly extending flanges 19 may be formed on the exterior of the casing 3 to which a suitable handle 20 may be pivotally secured as shown in Fig. 1.

By the construction above described, it will be noted that coverings for the shoe of the machine may be readily removed and yet easily but positively secured thereto. At the same time, the screw cap which is employed to effect a secure application of the shoe covering to the shoe serves not only to close the upper end of the wax reservoir but also serves as a bearing for the handle actuated shaft or piston rod by means of which the wax in the reservoir may be placed under pressure and thereby forced through the openings in the shoe to maintain the cloth covering the same in fairly well saturated condition.

While I have described my invention in its preferred embodiments, it is to be understood that the words which I have used are words of description rather than of limitation and that changes within the purview of the appended claims may be made without departing from the true scope and spirit of my invention in its broader aspects.

I claim:

1. A floor waxing and polishing machine comprising a shoe, a reservoir for a fluid extending upwardly from said shoe and secured thereto, a piston within said reservoir and a piston rod for operating said piston, a passage in said shoe communicating with the interior of said reservoir and the bottom of said shoe through which the fluid may discharge, a flexible covering for said shoe covering the bottom and sides thereof with its edge portions overlying the peripheral edges of the top of the shoe, a casing having its lower peripheral edges adapted to engage the top peripheral edges of the shoe to engage and secure the shoe covering therebetween; and means engageable with said reservoir and with said casing for clamping said casing to said shoe.

2. A floor waxing and polishing machine comprising a shoe, a reservoir for a fluid extending upwardly from said shoe and secured thereto, a piston within said reservoir and a piston rod for operating said piston, the upper end of said reservoir being cylindrical and threaded, a passage in said shoe communicating with the interior of said reservoir and the bottom of said shoe through which the fluid may discharge, a flexible covering

for said shoe covering the bottom and sides thereof with its edge portions overlying the peripheral edges of the top of the shoe, a casing having its lower peripheral edges adapted to engage the top peripheral edges of the shoe to engage and secure the shoe covering therebetween, and a screw threaded cap adapted threadedly to engage the upper screw threaded end of said reservoir and to engage with said casing for clamping said casing to said shoe.

3. A floor waxing and polishing machine comprising a shoe, a reservoir for a fluid extending upwardly from said shoe and secured thereto, a piston within said reservoir and a piston rod for operating said piston, the upper end of said reservoir being cylindrical and threaded, a passage in said shoe communicating with the interior of said reservoir and the bottom of said shoe through which the fluid may discharge, a flexible covering for said shoe covering the bottom and sides thereof with its edge portions overlying the peripheral edges of the top of the shoe, a casing having its lower peripheral edges adapted to engage the top peripheral edges of the shoe to engage and secure the shoe covering therebetween, and a screw threaded cap adapted threadedly to engage the upper screw threaded end of said reservoir and to engage with said casing for clamping said casing to said shoe, said cap having a central aperture therein to serve as a bearing for said piston rod and through which the upper end of said rod extends, and an operating handle secured to said upper end of said rod.

4. A floor waxing and polishing machine comprising a shoe having a peripherally extending rib upstanding from the top thereof, a reservoir for a fluid extending upwardly from said shoe and secured thereto, a piston within said reservoir and a piston rod for operating said piston, a passage in said shoe communicating with the interior of said reservoir and the bottom of said shoe through which the fluid may discharge, a flexible covering for said shoe covering the bottom and sides thereof with its edge portions overlying the peripheral edges of the top of the shoe, a hollow casing having its lower peripheral edges adapted to engage the top of the shoe adjacent the inner sides of the peripheral rib thereon whereby to engage and secure the shoe covering therebetween, and means engageable with said reservoir and with said casing for clamping said casing to said shoe.
